UNITED STATES PATENT OFFICE.

OWEN TAYLOR AND CHARLES C. TAYLOR, OF HUNTINGTON, WEST VIRGINIA, AS
SIGNORS TO JOHN EDWARD MILLER, SR., OF HUNTINGTON, WEST VIRGINIA.

MASON'S AND PLASTERER'S TOOL.

Application filed February 28, 1924. Serial No. 695,781.

To all whom it may concern:

Be it known that we, OWEN TAYLOR and CHARLES C. TAYLOR, citizens of the United States, residing at Huntington, in the county 5 of Cabell and State of West Virginia, have invented certain new and useful Improvements in Masons' and Plasterers' Tools; and we do hereby declare the following to be a full, clear, and exact description of the invention, such as will enable others skilled 10 in the art to which it appertains to make and use the same.

This invention has for its object to provide a combined trowel, pointer and beader for the use of masons and plasterers to enable the forming of different joints and for decorative work, the tool being in the nature of a trowel and provided with interchangeable points for adapting the same to 20 a variety of work.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 30 without departing from the spirit of the invention.

Referring to the accompanying drawings forming a part of the application:

Figure 1 is a perspective view of a tool 35 embodying the invention,

Figure 2 is a central longitudinal sectional view thereof, the dotted lines showing the front portion of the tool lowered,

Figure 3 is a transverse sectional view 40 on the line 3-3 of Figure 1, and

Figures 4, 5 and 6, are detail perspective views of different forms of interchangeable points.

Corresponding and like parts are referred 45 to in the following description and designated in the several views of the drawings by like reference characters.

The tool is elongated and hollow and comprises body and handle portions, the body portion including sections 1 and 2 which are hingedly connected at 3 and held in normal or working position by means of a suitable catch 4. The handle portion includes a grip 5 which has the section 2 attached. 50

55 The tool is hollow and a plunger 6 is ar-

ranged to operate therein and its rod 7 extends through the body and grip and terminates in a knob 8. The rod 7 is provided along a side with a plurality of ratchet teeth 9 which are adapted to coact with a latch lever 10 pivoted to the grip 5. The front end of the body is open, as indicated at 11, and any one of a plurality of points may be fitted thereto and held in place by means of a set screw 27 or other preferred 65 fastening.

Each of the points comprises a shank 13 and a tip 14, the latter being variously formed according to the particular nature of work in hand. Each of the points has an 70 opening 15 for the discharge of the mortar or other material to be applied, the same being forcibly ejected from the body of the tool by means of the plunger 6, which is positively and intermittently advanced by 75 means of the latch lever 10.

What is claimed is:

1. A tool of the character specified having a hollow body in sections hingedly connected together, one of the sections having a 80 handle portion, a catch for securing the sections in normal position, a plunger within the body provided with a rod extending therethrough and outwardly of the handle portion, said rod having ratchet teeth, a latch lever pivoted to the handle portion adapted to coact with the ratchet teeth to positively advance the plunger and forcibly expel material from the body, and said rod and plunger being retractile past the joint 85 of the sections so that one section may be swung relatively to the other section for reception of a charge.

2. A tool of the character specified having a hollow body in sections hingedly connected together, one of the sections having a handle portion, a catch for securing the sections in normal position, a plunger within the body provided with a rod extending therethrough and outwardly of the handle portion, said rod having ratchet teeth, a latch lever pivoted to the handle portion adapted to coact with the ratchet teeth to positively advance the plunger and forcibly expel material from the body, and said rod and plunger being retractile past the joint 95 of the sections so that one section may be swung relatively to the other section for reception of a charge, the body having a 100 forward end wall leading to said opening, 105

said body about the opening being substantially wedge shape, a point telescopically engageable with said wedge shape portion, and means to prevent accidental disengagement of said portion and point, and the forward end of the plunger conforming in shape to said wall.

In testimony whereof we affix our signatures in presence of two witnesses.

OWEN TAYLOR.

CHARLES C. TAYLOR.
